UNITED STATES PATENT OFFICE.

EUGENE D JEFFERSON, OF BOSTON, MASSACHUSETTS.

METHOD OF TREATING FIBROUS MATERIALS.

1,192,903.

Specification of Letters Patent. Patented Aug. 1, 1916.

Application filed January 13, 1915. Serial No. 1,959.

To all whom it may concern:

Be it known that I, EUGENE D. JEFFERSON, a citizen of the United States, residing at Boston, in the county of Suffolk and State of Massachusetts, have invented certain new and useful Improvements in: Methods of Treating Fibrous Materials; and I do hereby declare the following to be a full, clear, and exact description of the invention, such as will enable others skilled in the art to which it appertains to make and use the same.

The present invention relates to a method of treating fibrous materials, and more particularly to an alkaline treatment of fibrous materials.

While the method of the present invention may be employed in other industries, it is particularly applicable to the treatment of fibrous materials used in paper making. The fibrous materials, such as the chopped rags and the like which are used for making paper, are repeatedly and successively subjected to a boiling alkaline liquor and to steam. The chemical reaction due to the successive and repeated action of the heated liquor and steam upon the materials causes the materials to be softened and whitened, and in the case of colored materials causes the color to be discharged, more rapidly and completely than by the methods now in use. The treatment also saponifies any oils present in the materials and eliminates foreign materials such as the motes and hulls of cotton fiber.

The invention relates to certain other features which are particularly pointed out in the claims, the advantages of which will be apparent to those skilled in this art from the following description.

The method of the present invention is disclosed but not claimed in my copending application, Serial No. 671,226, which issued on February 16, 1915, as Letters Patent No. 1,128,451.

In the drawings which illustrate the preferred apparatus used in practising the present method, Figure 1 is a central vertical section through the boiling tank, Fig. 2 is an end view with part of the end closure of the tank broken away; Fig. 3 is a section on the line 3—3 of Fig. 1; and Figs. 4 and 5 illustrate a modification of the apparatus, Fig. 4 being a view partly in vertical sec-

tion, and Fig. 5 being a section along the line 5—5 of Fig. 4.

The method will be explained in conjunction with the description of the illustrated apparatus.

The illustrated apparatus is described as follows: The tank or vessel 1 is an air-tight horizontally disposed cylindrical drum which is supported on standards 2. Within the tank is a cylindrical rotary cage or hollow drum 3 in which the materials to be treated are packed. The cage 3 is made of sheet iron provided with a large number of perforations 4, so that the liquor has free access to the contents of the cage. The cage 3 is rotatably supported by means of a shaft 5. The shaft is journaled in bearings 6 and 7 at the ends of the tank. Beyond the bearing 7 is a stuffing box 8, which forms a tight joint about the shaft so that it may be rotated. The shaft 5 is slowly rotated by means of a gear 9 which is driven from a worm 10. The shaft 5 is hollow and is provided with a number of perforations 15 by means of which rinsing water may be introduced into the center of the cage 3. A union 16 provides a rotatable joint between the end of the shaft 5 and the water pipe 17. The cage 3 is provided on one side with a manhole 20 covered with a removable closure 21. Opposite the manhole 20 at the top of the tank 1 is a manhole 22, which is covered with a removable closure 23. The closure 23 is clamped down to make a steam tight cover. The materials are put into the cage 3 through the manholes 20 and 22. One end of the tank 1 is provided with a removable end closure or door 25 which is hung on hinges 26. A number of clamp screws 27 are provided for clamping the door to make a steam tight joint. The bearing 6 for the free end of the shaft 5 is formed on the inside of the door 25. The end of the cage is closed by means of a removable closure 30. The closure 30 is a circular perforated sheet metal disk provided with handles 31 so that it may be readily removed. The end of the cage is supported by a spider which comprises three arms 32, the inner ends of which are threaded in a hub 33 mounted on the shaft 5 and the outer ends of which are riveted to the cylindrical portion of the cage 3. The end closure 30 fits against the spider arms 32.

and is held in place by means of four retaining rods 35. The outer ends of the rods 35 fit through holes 36 in a collar 37 which is secured to the end of the cage 3 and which 5 projects beyond the closure 30. The inner ends of the rods 35 are secured to the hub 33 by means of thumb screws 38.

In order to support the free end of the cage 3 when the end shaft bearing 6 is removed upon opening the door 25, two supporting rolls 40 are provided. The rolls 40 are mounted on a bracket 41 which is secured at the top of the end frame 42 of the tank 1. The rolls 40 project inside of the 15 collar 37, so that when the door 25 is opened, the rolls 40 support the weight of the cage. During the normal operation of the apparatus when the door 25 is closed, the bearing 6 supports the weight of the cage, there 20 being little clearance between the inside of the collar 37 and the rolls 40. Two rollers 43 on the inside of the end frame of the tank engage the outside of the collar 37 and prevent the cage 3 from striking the sides of 25 the tank. The end closures 25 and 30 are provided to give a large opening through which the materials may be quickly emptied from the cage.

The lower part of the tank 1 is provided 30 with a steam jacket 50 for the purpose of boiling the liquor in the tank. The steam is admitted to the steam jacket through the pipe 51. The pipe 51 is provided with a reducing or throttling valve 52, which has an 35 actuating connection through the pipe 53 to the inside of the tank 1. The reducing valve 52 is of a well known construction and need not be described in detail. The valve 52 is set so that when the steam pressure in 40 the tank 1 rises to thirty pounds, the pressure in the tank 1 is communicated to the valve 52 through the actuator pipe 53 and causes it to throttle the steam. The reducing valve 52 is set so that the steam is admitted 45 to the steam jacket 50 at such a rate as to maintain a pressure of about thirty pounds to the square inch in the tank 1 due to the boiling of the liquor therein. Connected to the pipe 53 is an automatic vent 54, which 50 is of a well known construction. The purpose of the vent is to allow the air to escape from the tank when the liquor is boiled but to prevent the escape of the steam. The vent 54 is preferably set so that when the 55 pressure in the tank is less than one-half pound to the square inch the vent is open, and when the pressure in the tank exceeds one-half pound to the square inch the vent is automatically closed. This permits the air 60 to be driven out of the tank and at the same time prevents any appreciable amount of steam from escaping when the tank liquor is heated to a boil. The vent 54 is small enough so that a one-half pound steam pressure can 65 be built up in the tank to close the open vent

when the boiling has begun. The drip water from the steam jacket 50 runs away through the drip pipe 55. A safety valve 56 is provided as a precaution against accidentally excessive pressures in the tank.

A pipe connection 60 is provided at the bottom of the tank and serves for the introduction of the liquor into the tank and for the drawing off of the liquor and the final drawing off of the rinsing water. An overflow pipe 61 is provided for the overflow of rinsing water during the rinsing of the materials. It is to be understood, of course, that the pipes 17, 60 and 61 are provided with suitable valves (not shown).

A plate or partition 70 extends between the shaft 5 and the inside of the cage 3, and extends the full length of the drum. The purpose of the plate 70 is to prevent the materials from sliding around in the cage 3 85 when it is rotated. Thus the charge of material is rotated with the cage and the materials are carried up and down in the tank.

The method is carried out as follows:— The cage 3 is packed full of the materials 90 to be treated and the manhole closures 21 and 23 are clamped in place. The tank 1 is filled about one-half full with the alkaline treating liquor. This liquor usually contains about 4% of slaked lime and 1% of soda ash. 95 The cage 3 is then set slowly rotating. The cage rotates once about every five minutes. The steam is admitted through the pipe 51 to the steam jacket 50 for the purpose of boiling the liquor. As the liquor commences 100 to boil, the steam generated from the liquor drives out the air from the tank 1 and then automatically closes the vent 54. The steam pressure in the tank 1 rises to about thirty pounds per square inch and is maintained 105 for about five or six hours during which the cage 3 is continuously rotated.

The materials in the cage 3 are successively and repeatedly immersed in the boiling liquor in the bottom of the tank and then subjected to the steam in the top of the tank. The cage 3 rotates slowly enough 110 so that the steam has time to penetrate the goods in the then uppermost part of the cage 3. The steam in the top of the tank is 115 generated from the boiling of the alkaline liquor and apparently contains some of the alkaline liquor entrained in very finely divided condition. This steam with entrained alkali will be hereinafter termed "alkali 120 fumes" for the purpose of convenience. The successive and repeated action of the boiling alkaline liquor and the alkali fume causes a remarkable chemical reaction upon the materials, particularly in discharging the 125 color and bleaching them. This is believed to be due to the presence in the steam of the finely divided entrained particles of alkali. The presence of alkali in the steam is indicated by the character of the steam. The 130

steam escaping into the air even in small quantities produces a choking sensation and smells strongly of alkali. While the exact reason for the effect of the successive and repeated action of the boiling alkaline liquor and the alkali fume is not perfectly understood, its operation is very efficient in discharging and whitening the materials. The successive and repeated immersions of the goods in the boiling liquor with the consequent draining gives an effective washing action. It will be seen that the cage in which the goods are held is spaced apart from the tank. This space between the cage and the tank serves as a depository for dirt, gravel, precipitates from the chemical reactions, undissolved alkalies, etc. The cage is rotated so slowly that this foreign material is not stirred up much and, consequently, is not brought back into contact with the goods after it has been once deposited. The boiling of the goods under pressure, therefore, serves not only to bleach them and dissolve foreign materials such as silex, but also thoroughly washes the goods. It is to be noted that the liquor in the tank is boiled by heat externally applied by means of the steam jacket 50, so that the alkaline liquor is not diluted nor its level raised, as would be the case if the steam were introduced directly into the tank to boil the liquor. The alkali boil is continued about five or six hours. Then the steam is shut off and the alkaline liquor drained off. The materials are then thoroughly rinsed to free them of alkali and to cool them before any air or oxygen is permitted to come in contact with them. If the materials are exposed to the air while they are wet with the hot alkali, an oxycellulose will be formed which breaks down the fiber of the materials. After the alkaline liquor is drained off from the tank the heat of the body of the materials will prevent the entrance of air into the tank while they are being rinsed. The rinsing operation also acts to remove all the coloring matter from the materials which has been made soluble by the successive and repeated action of the alkaline liquor and alkali fume. The rinsing water is introduced through the perforated shaft 5 and overflows through the overflow pipe 61. The rinsing is continued about an hour or two. During the rinsing, the cage 3 is continuously rotated. The rags are so cleansed and cooled by the rinsing operation that no fermentation takes place when the rags are discharged from the tank. The usual practice has heretofore been to blow off the rags hot after the alkali boil, and the alkaline liquor was left in the rags to such an extent that a saponified oil was commonly employed in the washer to prevent foaming. This is obviated by rinsing and cooling the materials before they are discharged.

After the materials have been rinsed, the rinsing water is all drained off through the pipe 60 and the door 25 opened and the closure 30 removed. The cage 3 is then rotated to discharge the materials through the open ends of the cage and tank.

The modified apparatus illustrated in Figs. 4 and 5 is described as follows: The tank or vessel 101 is an air tight horizontally disposed cylindrical drum which is rotatably supported upon standards 102. Within the vessel 101 is a cage or hollow drum 103 which is rigidly secured in any convenient way to the tank 101. The cage 103 is packed with the materials to be treated. The cage 103 is provided with a large number of perforations 104 so that the liquor may freely pass through the walls of the cage. Between the tank 101 and the cage 103 are coils of steam pipe 105 by means of which the liquor in the drum is boiled. The cage 103 serves to keep the materials out of direct contact with the hot steam pipes so as not to scorch them. The steam enters through a steam supply pipe 106 and the condensed water runs off through the drip pipe 107. The pipes 106, 107 are provided with rotatable joints 108. The treating liquor and rinsing water may be run into the tank through a pipe 109 and the rinsing water is allowed to run off through an overflow pipe 110. The pipes 109, 110 are provided with rotatable joints 111 so that the tank may be rotated. The goods are packed in the cage 103 and are removed therefrom through manholes 112. The pipe 109 or 110 is preferably connected with a safety valve, not shown, which prevents dangerous pressures in the tank 101. The steam which is admitted through the supply pipe 106 is preferably throttled by an automatic throttling valve, not shown, which is controlled by the pressure in the tank 101 and operates similarly to the reducing valve 52 shown in Fig. 1. The rinsing water coming into the tank through the pipe connection 109 passes into a hollow perforated pipe 113 which is centrally located in the cage 103 so that the goods may be thoroughly rinsed. A retaining or baffle plate 130, similar to the baffle plate 70 shown in Fig. 3, is provided for the purpose of carrying the goods around with the drum when it is rotated.

The tank 101 is provided with a plurality of air vents 120. Each vent consists of a valve to the handle of which is connected a lever 121 which is turned to open or close the valve. A stop 122 is arranged in the path of the outer end of the levers 121 and another stop 123, indicated in dotted lines in Fig. 5, lies in the path of the inner ends of the levers 121. The tank is rotated in the direction of the arrow in Fig. 5. When a lever 121 strikes the stop 122 it opens its 125 130 135 140 145 150 155 160 165 170 175 180 185 190 195 200 205 210 215 220 225 230 235 240 245 250 255 260 265 270 275 280 285 290 295 300 305 vent valve 120 and when a lever 121 strikes the stop 123 it closes its vent valve 120. Consequently, the vents are opened at the top of the tank and are closed at the bottom of the tank during the rotation of the tank. This allows the air to escape from the top of the tank, but prevents the liquor from escaping through the vents.

After the goods are packed in the cage 103 the manholes 112 are closed and the tank is half filled with the alkaline liquor. The tank is rotated and steam is let into the steam coils 105. The steam pipes 105 bring the liquor to a boil and the steam generated from the boiling alkaline liquor drives out the air. The stops 122 and 123, are, during this time, held in the paths of the ends of the levers 121 so as to keep the vent valves open at the top of the tank. After the generated steam has expelled the air from the tank the stop 122 is first removed and then after the vents are all closed the stop 123 is removed. The expulsion of the air from the tank is important in that the goods are not scorched or weakened by the oxidizing effect of air on the heated goods. While it is of particular importance to expel the air during the process of treating the goods in which the goods are lifted out of the treating liquor, it is also important and desirable to expel the air from the tank in which the goods are treated with the boiling alkaline liquor in processes in which the goods are not lifted out of the liquor. For example, the usual process in which the goods remain immersed in the liquor is improved by providing the boiling kier or tank with vents which permit the air to escape so that the goods at the surface of the liquor are not chemically affected by oxygen. The step above described of expelling air from a boiling kier is not solely applicable to the method of treating goods in which they are alternately subjected to the treating liquor and steam but may be employed in other processes as, for example, an improvement in the usual process of alkali boiling paper stock. The tank 101 is slowly rotated so that the liquor has a good chance to drain out of the goods which are lifted above the liquor level. The steam or alkali fume penetrates the goods and, as above pointed out, assists in the chemical reaction of discharging the color and whitening the goods. This chemical reaction is further accentuated by the drying effect of the steam or alkali fume in the area above the liquor. The steam is in contact with the heating coils 105 which are above the liquor level and these heating coils serve to dry the steam. The comparatively long period of time in which the goods are held in the steam space allows the dried alkali fumes to dry the goods and concentrate the alkalis held by them. The goods are held in the steam space long enough to

be thoroughly penetrated by the alkali fumes. The drying action of the heating coils and the dry alkali fumes above the liquor level also materially aids in bleaching the goods.

It will be noted that in the apparatus shown in Figs. 4 and 5, as well as the apparatus shown in Figs. 1 and 3, the steam which is used for boiling the liquor does not come into contact with the liquor but is carried through heating coils or a steam jacket. In this way the liquor level in the tank is not increased nor is the liquor weakened, as is the case when boiling is carried out by introducing the steam directly into the tank. Moreover, in the apparatus shown in Figs. 4 and 5, the steam coils which are above the liquor level, serve to superheat the steam, a thing impossible when the liquor is boiled by the direct introduction of steam into it. Heating the liquor by means of the steam jacket or steam coils is known to the trade as heating "by radiation" as distinguished from heating by introducing the steam directly into the liquor which is to be boiled, which is known in the trade as "direct" heating. The term "radiation" as used in the claims is to be understood as having the usage common in the trade.

The materials containing indigo blue have been particularly troublesome for the paper maker. The indigo blue is more difficult to discharge than most dyes. For the treatment of materials containing indigo blue, the spent lime liquor from a previous boil is used and to it is added about five per cent. caustic soda, six per cent. soda ash and two per cent. green olive soap. The use of this alkaline liquor according to the method of the present invention in which the materials are subjected successively and repeatedly to the action of the liquor and steam, will eliminate indigo blue in the boil, and by the addition of a slight amount of chlorid of lime to the rinsing water the materials will come out white.

The usual practice heretofore has been to boil the materials such as the chopped rags in a closed vessel in which the materials are immersed in the boiling liquor substantially all of the time. In the case of colored rags this treatment has had to be followed by a subsequent bleaching with chlorin in which the goods have been treated with chlorid of lime and have then been allowed to lie for a long time in the drainers. This chlorin treatment, while necessary to whiten the materials, has weakened the fiber, not to take into account the time and labor consumed. One of the advantages of the present invention is that the color is so thoroughly discharged and the rags sufficiently whitened that it is unnecessary to let the rags lie in the drainers for the length of time heretofore necessary to complete the bleach.

While the method of the present invention has been specifically described and particularly with reference to the treatment of paper stock, it is to be understood that the present invention is not limited to all of the described details or to its application to paper making, but may be used in other processes and industries within the scope of the invention as set forth in the following 10 claims.

I claim—

1. The method of treating fibrous materials which comprises, placing the materials in a closed pressure tight vessel containing an alkaline liquor, removing air or oxidizing gases from the vessel and successively and repeatedly immersing the materials in and withdrawing them from the liquor while maintaining the different parts of the materials in approximately the same relative position.

2. The method of treating fibrous materials which comprises, placing the materials in a closed vessel containing an alkaline liquor, boiling the liquor to generate steam, and successively and repeatedly immersing all of the materials in and withdrawing them from the liquor during the boil while maintaining the different parts of the materials in approximately the same relative position.

3. The method of treating fibrous materials which comprises, placing the materials in a closed vessel containing an alkaline liquor, boiling the liquor to generate steam, and successively and repeatedly immersing all of the materials in and withdrawing them from the liquor during the boil while maintaining the different parts of the materials approximately in the same relative position and the concentration of the liquor approximately constant.

4. The method of treating fibrous materials which comprises, subjecting the materials to the successive and repeated actions of a boiling lime liquor and steam generated from the liquor in a closed vessel from which the air has been expelled by the steam, and completing the treatment after the expulsion of air without the admission of external substances into the vessel.

5. The method of treating fibrous materials which comprises, placing the materials in a closed vessel with an alkaline liquor, boiling the liquor by externally applied heat to expel the air from the vessel and fill it with steam under pressure, and successively and repeatedly immersing the materials in and withdrawing them from the boiling liquor to alternately subject them to the action of the liquor and the steam generated from the liquor while maintaining the different parts of the materials in the same relative position.

6. The method of treating fibrous materials

which comprises, placing the materials in a closed vessel, boiling the materials, repeatedly immersing the materials in and holding them out of the liquor, and maintaining sufficient liquor in the vessel during the boil so that in the movement of the materials each part will be drained of and wet with the liquor.

7. The method of treating fibrous materials which comprises, placing the materials in a closed vessel with an alkaline liquor, 75 boiling the liquor by external heat to generate steam therefrom, repeatedly holding the materials in and retaining them out of the boiling liquor, and engaging the height of the liquor throughout the boiling operation 80 so that in the movement of the materials each part of the materials will be drained of and wet with the liquor.

8. The method of treating fibrous materials which consists in subjecting them to the successive and repeated action of a boiling lime liquor and steam generated from the boiling liquor in a closed vessel from which the air has been expelled by the steam.

9. The method of washing and discharging coloring matter from fibrous materials which comprises placing the materials in a pressure tight tank containing a lime liquor, boiling the liquor, subjecting all of the materials to the repeated action of the liquor 95 and the steam above the liquor during the boil, discharging the lime liquor and rinsing the materials to remove the lime liquor and coloring matter before admitting air into the tank and cooling the materials before 100 they are discharged from the tank.

10. The method of treating fibrous materials which consists in putting them in a closed vessel with an alkaline liquor, in boiling the liquor by externally applied heat to 105 expel the air from the vessel and fill it with steam from the boiling liquor, and in successively and repeatedly immersing the materials in and withdrawing them from the boiling liquor to alternately subject them to 110 the action of the liquor and the steam generated from the boiling liquor.

11. The method of treating fibrous materials which comprises placing the materials in a closed tank containing an alkaline liquor, boiling the liquor, subjecting all of the materials repeatedly to the separate action of the liquor and the steam generated from the liquor during the boil, discharging the alkaline liquor and forcing a rinsing 120 water through the materials from the center to the periphery thereof while rotating the materials to remove the alkaline liquor and cool the materials.

12. The method of treating fibrous materials which consists in treating the materials with a hot alkaline liquor under pressure in a closed vessel, in the absence of air, and in rinsing and cooling the materials before air is admitted to the vessel to pre- 130

vent subsequent fomentation and the formation of oxycellulose.

13. The method of treating fibrous materials which consists in putting them in a closed vessel together with an alkaline liquor in boiling the liquor by external heat to generate alkaline fumes and expel the air from the vessel, and in subjecting the materials to the liquor and alkaline fumes in 10 the absence of air.

14. The method of treating fibrous materials which consists in putting them in a closed vessel together with an alkaline liquor, in heating the liquor in the vessel by 15 "radiation" to generate steam and fill the vessel with steam so that the liquor is not weakened and the steam is generated from the alkaline liquor and in maintaining the materials out of contact with the heat radiating surfaces.

15. The method of treating fibrous materials which consists in boiling the materials in a tank and subjecting all parts of the materials during the boil to the separate

25 successive and repeated actions of an alkaline liquor and steam generated from the alkaline liquor, and drying the materials in the steam.

16. The method of treating fibrous materials which consists in boiling the materials in a tank and subjecting all of them to the separate successive and repeated action during the boil of a boiling alkaline liquor and dried fumes which have been 35 generated from the boiling liquor.

17. The method of treating fibrous materials which comprises, placing the materials in a foraminated receptacle within a pressure tight tank partially filled with an 40 alkaline liquor, by heating the tank walls, maintaining a space between the foraminated vessel and the tank to hold the materials away from the tank walls boiling the liquor and rotating the materials to successively and repeatedly immerse them in and withdraw them from the liquor.

18. The method of treating fibrous materials which comprises placing the materials in a vessel, adding an alkali liquor 50 which will stand at about one half the height of the interior of the vessel heating the liquid area by radiation to generate steam, successively and repeatedly carrying the goods during the boil from the steam area

to the liquid area and back again, and heating the steam area by radiation to heat the generated steam and dry the materials.

19. The method of treating fibrous materials which comprises, placing the materials in a receptacle within a closed tank 60 containing an alkaline liquor, and slowly moving the receptacle to successively and repeatedly wet the materials with and drain them of the liquor and prevent the receptacle from touching the vessel to reserve a 65 space for the collection of foreign substances washed from the materials.

20. The method of treating fibrous materials which consists in placing the materials in a closed vessel containing an alkaline liquor, boiling the liquor to generate steam, successively and repeatedly immersing the materials in and withdrawing them from the liquor during the boil, and gaging the rate of movement of the materials so 70 that they will be immersed in or withdrawn from the liquor not less than one minute each.

21. The method of treating fibrous materials which comprises, placing the materials in a closed vessel containing an alkaline liquor, boiling the liquor to generate alkali fumes, uniformly heating the surface of the vessel successively and repeatedly immersing the materials in and withdrawing them from the liquor, and gaging the movement of the materials so that they will remain out of the liquor for a sufficient period to drain and be penetrated and dried by the fumes.

22. The method of treating fibrous materials which comprises placing the materials in a pressure tight tank with an alkaline liquor, heating the liquor by radiation of a high pressure steam to generate an alkali 95 fume in the tank, venting the tank until an appreciable steam pressure is formed therein to drive off air and gases, closing the vents and continuing the high pressure steam heating until the pressure of not less 100 than twenty five pounds per square inch is generated in the tank, and then throttling the heating steam to maintain a substantial uniform pressure in the tank.

EUGENE D. JEFFERSON.

Witnesses:

GEORGE E. STIBBINS,
BESSIE J. SMITH.

It is hereby certified that in Letters Patent No. 1,192,903, granted August 1, 1916, upon the application of Eugene D. Jefferson, of Boston, Massachusetts, for an improvement in "Methods of Treating Fibrous Materials," errors appear in the printed specification requiring correction as follows: Page 3, line 8, after the word "discharging" insert the words *the color*; page 5, line 79, claim 7, for the word "engaging" read *gaging*; and that the said Letters Patent should be read with these corrections therein that the same may conform to the record of the case in the Patent Office.

Signed and sealed this 24th day of October, A. D., 1916.

[SEAL.]

F. W. H. CLAY,
Acting Commissioner of Patents.
